UNITED STATES PATENT OFFICE

110,013

DESIGN FOR AN AUTOMOBILE TRANSPORT BODY

William E. Baker, Detroit, Mich., assignor to
Whitehead & Kales Company, River Rouge,
Mich., a corporation of Michigan

Application April 12, 1937, Serial No. 68,712

Term of patent 14 years

To all whom it may concern:

Be it known that I, William E. Baker, a citizen of the United States of America, residing at Detroit, in the county of Wayne and State of Michigan, have invented a new, original, and ornamental Design for an Automobile Transport Body, of which the following is a specification, reference being had therein to the accompanying drawing, forming a part thereof, wherein:

Figure 1 is a side elevation of an automobile transport body showing my new design;

Figure 2 is a front perspective view thereof;
Figure 3 is a rear perspective view thereof; and
Figure 4 is a top perspective view thereof.

The dominant feature of the present design is the top portion of the body.

I claim:

The ornamental design for an automobile transport body substantially as shown and described.

WILLIAM E. BAKER.
